UNITED STATES PATENT OFFICE

2,224,921

UNWINDING OF CONTINUOUS FILAMENT
YARNS

William Pool, Spondon, near Derby, England, assignor to Celanese Corporation of America, a corporation of Delaware

Application October 6, 1938, Serial No. 233,534
In Great Britain October 29, 1937

8 Claims. (Cl. 19—1)

This invention relates to the unwinding of continuous filament yarns from bundles or packages into which they have been formed.

According to the present invention continuous filaments wound on a package are unwound as a plurality of ends by positively rotating the package about its axis and subjecting each of the ends to the action of a fluid stream so as to exert thereon a non-positive pull to draw the ends from the package at a rate permitted by the rate of positive rotation of said package. The rotation of the package support frees the continuous filaments for removal from the package at the peripheral speed of the surface of the package, and the non-positive pull serves to keep the ends separate by gently withdrawing the ends apart and preventing odd filaments of one end from being caught in the other end. Conveniently, compressed air jets may be used to pull the ends as they leave the package.

While the invention is generally applicable to withdrawing from a single package a plurality of ends, especially where the filaments contain very little or no twist, it is of particular advantage in withdrawing filaments that have been laid substantially as a single end by a single traverse member, since it permits the separation of the ends notwithstanding the closeness of the positions at which they have been laid on the package. Thus, for example, the product of a single spinning jet in a spinning machine may be led to a traverse member comprising two guide openings, the product being divided into two ends passed one through each of the openings. The two openings serve to lay each end with substantially the same traverse, to cause one end to follow a tangential path slightly different from that followed by the other end, with the result that the two ends are laid slightly out of phase.

When unwinding takes place by a positive rotation of the package support, the out of phase positioning of the two ends helps them to leave the package separately, and the non-positive pull exerted on them keeps odd filaments of one end from straying into the other end. The package support may rotate at a constant angular speed so that the rate of delivery diminishes with the decrease in package diameter, or the speed of the support may be adjusted continuously or by steps during unwinding so as to compensate for decrease in package diameter.

The invention may be employed in processes such as those described in U. S. applications S. Nos. 155,226 filed 23rd July 1937 and 168,862 filed 14th October 1937 for the direct production from

continuous filaments of a staple fibre product, and enables more than one such product to be obtained from a single package of continuous filaments.

By way of example two forms of unwinding apparatus according to the invention will now be described in greater detail with reference to the accompanying drawing in which

Figs. 1 and 2 are a front elevation and a side elevation respectively of one form of unwinding apparatus according to the invention; and

Fig. 3 is a front elevation of a modification of the apparatus shown in Figs. 1 and 2.

Referring to Figs. 1 and 2, 1 is a package of continuous filaments, which are wound as two ends 2 each of which is in the form of a bundle of continuous filaments. The package 1 is provided with flanges 3 each of which rests between a pair of friction rollers 4 mounted upon shafts 5 and driven from a shaft 6 by means of a pair of gears 7, and a chain 8 running round sprockets 9. By these means the package 1 is positively rotated at a constant angular speed. The ends 2 are drawn from the package 1 at a rate controlled by the rate of rotation of the package. For this purpose the ends 2 after passing through a guide 10 and round a roller 11, provided for a purpose to be described hereafter, pass through a guide tube 12 having an air nozzle 13 supplied with compressed air through a pipe 14 and valve 15 from a header 16. The tractive effort of the blast of air from the nozzle 13 passing through the tube 12 draws the end 2 gently from the package 1 so that the end 2 leaves the package at the rate permitted by the rate of rotation of the package as determined by the speed of the friction wheels 4.

From the guide tube 12 the end 2 proceeds to an apparatus of the kind described in U. S. application S. No. 155,226 by means of which it is converted directly into a staple fibre yarn. This comprises a guide member 17 having an internal air jet 18 supplied with air through a pipe 19 from the header 16. The jet 18 blows the filaments out through a diverging nozzle 20 whose mouth is of flattened cross-section as shown in Fig. 1 so that the filaments of the end 2 emerge as a wide flat band of separated filaments. The filaments are severed at regular intervals by means of a cutter 21 of the hair clipper type operated by an arm 22, the cutter being obliquely set so as to cut the wide band of filaments issuing from the nozzle 20 in such a way that the ends of the fibres so produced are staggered. The groups of fibres so cut are received on a band 23

and are held there by suction induced by a suction pipe 24, the band 23 conducting them to a pair of rubbing bands 25 by means of which they are compacted into a continuous coherent staple fibre product as described in U. S. application S. No. 155,226. As will be seen from Fig. 1 the guide 10, roller 11, guide tube 12 and all subsequent parts are duplicated so that the two ends 2 drawn from the package 1 are separately handled after they leave the package.

In order to assist the flat diverging nozzle 20 to separate the filaments into a flat band the guide 10 and roller 11 are provided, the roller 11 being provided, as described in U. S. application S. No. 233,535, filed October 6, 1938, with a surface 26 of material such as rubber, gutta percha, or like substance suitably removed in the electrostatic series from the basic material of the filaments. The roller 11 is driven from the shaft 6 by means of a belt 27 and pulleys 28 and 29 mounted respectively on the shaft 6 and on the shaft 30 carrying the rollers 11. The dimensions of the pulleys 28 and 29 are such that the peripheral speed of the roller 11 is greater than that of the end 2 passing over it so that frictional contact with the roller 11 does not hinder the guide tube 12 and nozzle 13 in the drawing of the ends 2 from the package 1. The guide 10 is adjustable so that the arc of contact of the end 2 on the roller 11 may be adjusted so as to adjust the degree of electrification produced. For this purpose the guide 10 is formed on the end of a rod 31 passing through small holes in spring members 32 mounted on a bar 33. As the members spring outwards the holes in them through which the rod 31 passes grip the rod, but by pinching the members 32 together the rod 31 is released and the position of the guide 10 may be adjusted. The bar 33 may be traversed to and fro along the length of the rollers 11 so as to change the part of the surface of the rollers 11 with which the ends 2 make contact.

In Fig. 3 is shown a form of apparatus suitable for delivering filaments at a constant linear rate. The package 35 is mounted between a pair of driving rollers 36, which are similar to the driving wheels 4 described with reference to Figs. 1 and 2, but, instead of contacting only with flanges at the ends of the package, extend across the whole width of the package 35 and contact with the surface of the package, the flanges 3 described with reference to Figs. 1 and 2 not being employed. By these means the package 35 is rotated at a constant peripheral speed and the ends 2 leaving the package 35 are permitted to be drawn away at a constant linear speed. The ends 2 drawn from the package 35 pass through guides 37 mounted on a bar 38, and proceed to a guide tube 12, being subsequently handled in the manner described with reference to Figs. 1 and 2.

Having described my invention, what I desire to secure by Letters Patent is:

1. A method of unwinding continuous filaments as a plurality of ends from a package on which they are wound, said method comprising rotating said package about its axis at a definite rate and subjecting each of the ends separately and simultaneously to the action of a fluid stream so as to exert thereon a non-positive pull to draw the ends from the package at a rate permitted by the rate of rotation of said package.

2. A method of unwinding continuous filaments as a plurality of ends from a package on which they are wound, said method comprising

rotating said package about its axis at a definite rate and subjecting each of the ends separately and simultaneously to the action of a stream of compressed air so as to exert thereon a non-positive pull to draw the ends from the package at a rate permitted by the rate of rotation of said package.

3. A method of unwinding continuous filaments as a plurality of ends from a package on which they are wound, said method comprising rotating said package about its axis at a constant angular speed and subjecting each of the ends separately and simultaneously to the action of a fluid stream so as to exert thereon a non-positive pull to draw the ends from the package at a rate permitted by the rate of rotation of said package.

4. A method of unwinding continuous filaments as a plurality of ends from a package on which they are wound, said method comprising rotating said package about its axis at a constant peripheral speed and subjecting each of the ends separately and simultaneously to the action of a fluid stream so as to exert thereon a non-positive pull to draw the ends from the package at a rate permitted by the rate of rotation of said package.

5. A method of converting into a plurality of staple fiber products a plurality of ends of continuous filaments wound on a single package, said method comprising rotating said package about its axis at a definite rate, subjecting each of the ends separately and simultaneously to the action of a fluid stream so as to exert thereon a non-positive pull to draw the ends from the package at a rate permitted by the rate of rotation of said package, separating the filaments of each end from one another, cutting from each end successive groups of separated fibers in such a manner that the successive groups overlap and compacting the succession of groups of fibers from each end into a continuous staple fiber product.

6. A method of converting into a plurality of staple fiber products a plurality of ends of continuous filaments wound on a single package, said method comprising rotating said package about its axis at a definite rate, subjecting each of the ends separately and simultaneously to the action of a fluid stream so as to exert thereon a non-positive pull to draw the ends from the package at a rate permitted by the rate of rotation of said package and in such a manner as to separate the filaments of each end from one another, cutting from each end successive groups of separated fibers in such a manner that the successive groups overlap and compacting the succession of groups of fibers from each end into a continuous staple fiber product.

7. A method of converting into a plurality of staple fiber products a plurality of ends of continuous filaments wound on a single package, said method comprising rotating said package about its axis at a definite rate, subjecting each of the ends separately and simultaneously to the action of a fluid stream so as to exert thereon a non-positive pull to draw the ends from the package at a rate permitted by the rate of rotation of said package, imparting to the filaments of each end a charge of static electricity so as to separate said filaments from one another, cutting from each end successive groups of separated fibers in such a manner that the successive groups overlap and compacting the succession of groups of fibers from each end into a continuous staple fiber product.

of groups of fibers from each end into a continuous staple fiber product.

8. Apparatus for unwinding continuous filaments as a plurality of ends from a package on which they are wound, said apparatus comprising means for rotating the package about its axis at a definite rate, a plurality of jets each adapted to apply a fluid stream to an end of filaments leaving said package so as to exert a non-

positive pull upon said end, and a roller surfaced with material remote in the electrostatic series from the substance of the filaments and disposed between the package rotating means and the jet so as to make rubbing contact with the filaments and to impart to said filaments a charge of static electricity.
